J. WEARHAM

PIANO PLAYER

Filed June 20, 1922

FIG. I.

UNITED STATES PATENT OFFICE.

JOHN WEARHAM, OF WESTMINSTER, LONDON, ENGLAND, ASSIGNOR TO VICKERS LIMITED, OF WESTMINSTER, LONDON, ENGLAND, A BRITISH COMPANY.

PIANO PLAYER.

Application filed June 20, 1922. Serial No. 569,598.

To all whom it may concern:

Be it known that I, JOHN WEARHAM, a subject of the King of Great Britain, residing at Vickers House, Broadway, Westminster, in the county of London, England, have invented certain new and useful Improvements in or Relating to Piano Players, of which the following is a specification.

This invention relates to piano players of the kind constructed to form a more or less self-contained unit which is clamped or otherwise detachably connected to the piano in such a position that the strikers can operate upon the keys of the piano.

According to the present invention the piano player is so constructed and arranged that it can be folded, collapsed or divided into sections in order to reduce its length when removed from the piano so that it can be packed into a comparatively small space and can be thus easily carried by the owner who can take his piano player with him to houses possessing a piano unprovided with a mechanical player and readily place it in its operative position on said piano for playing. In the preferred form of the invention the piano player may comprise a wind box or chest which preferably also serves as a carrier for most of the operating mechanism. This box may be made in two parts which communicate with each other when in the operative position and which may be hinged together so that when removed from the piano one part can be folded against the other and thus reduce the length as mentioned above.

The two parts of the piano player when in the operative position are held together by means of suitable catches and the hinge about which these two parts turn may be vertically disposed at the back of the box.

The strikers may be held in the inoperative position by means of one or more sliding shelves or plates which when the piano player is in place for use, are withdrawn to allow the strikers to come into contact with the keys of the piano. The said shelves or plates when in position completely cover the strikers and the pistons, bellows or other operating devices and thus protect these parts from injury. This feature of the invention can also be used in conjunction with a piano player made in a single length and in this case a single shelf or plate of the same length as the piano player may be employed,

although if desired two or more shorter shelves or plates could be used.

In order that the said invention may be more fully understood and readily carried into effect, the same will be more fully described with reference to the accompanying drawings, in which—

Figure 1 is a view showing a piano player constructed in accordance with this invention in position on a piano.

Figure 2 is a view of the piano player in its folded position in a carrying case which is indicated by chain lines.

Figure 3 is a transverse section through the wind box or chest showing one of the aforesaid shelves or trays.

Figure 4 is a diagram showing the air connections at the plane of division between the two parts of the wind box or chest for a pneumatically operated piano player.

In the constructional form shown by Figures 1 and 2 A, A¹ are the two parts of the wind box or chest and A² is a central portion carrying the music roll. B is the tracker bar and B¹ is the driving cylinder which, as shown, is operated by hand plates or discs C, C¹ which are arranged at each side of the central portion A² and which, together with their associated parts, are fully described in the specification of British Patent No. 189,175. The said driving cylinder may, however, be operated in any other desired manner, for example by a small clockwork, pneumatic or electric motor or by means of weights which may advantageously consist of light metal vessels adapted to hold water. C² is the pointer of a speed indicator which may be driven in any desired manner such as that described in the specification of the said patent.

In the construction shown the piano player is arranged above the keys of the piano with the outer ends resting upon the end blocks of the keyboard. To render the player capable of use with a piano having end blocks of different lengths, adjustable members a, a are provided, these members being carried by rods a¹, a¹ which slidably enter the casing of the piano player at the ends and are held in the required position by thumb screws a², a². One of the said adjustable members carries a plate a³ which, by a screw or cam device operated by a handle a⁴, can be forced against the upright portion of the piano at the end of the end

block to hold the player in position as is well understood.

The two parts A, A¹ of the windbox or chest are hinged together at A³, the hinge 5 in the example shown by Figures 1 and 2 being at one side of the central portion A² and at the back part thereof. This enables the player to be folded as shown in Figure 2 and leaves spaces in the carrying case A^x 10 for spare music rolls a^x, a^x . . . In a pneumatic player the tubes b, b (Figure 5) . . . leading from the tracker bar B to the pneumatics in the part A of the wind box are interrupted as shown and are sealed into a 15 plate A^{1x}. The other portions of these tubes are sealed into a plate A^{xx} in corresponding positions so that when the player is in the operative position with the plate A^{xx} brought flush against the plate A^{1x} by turning the 20 part A about the hinge A³, communication is established between the two portions of each tube. A similar arrangement is provided for the large duct A⁰ connecting the two pumping systems when two separate 25 systems are employed. The contiguous faces of the said plates may be coated with rubber or other suitable material for ensuring an airtight joint and these plates may have associated with them a flap which when 30 the player is in the folded condition shown in Figure 2 presses across both the said faces to exclude dust. Instead of the arrangement described by which communication between the pipe and duct portions is broken 35 when the piano player is folded and is established when the plates A^{xx} and A^{1x} are brought together, the ends of the pipes and ducts sealed into the said plates may be connected by flexible tubes of such length as to 40 permit the folding movements to occur.

A⁴, A⁴ (Figures 1 and 3) represent the aforesaid shelves or plates which are mounted in grooves beneath the two parts of the piano player, each plate being of a length 45 corresponding to the lengths of the said two portions. These plates are intended when pressed inwards to co-act with the portions A⁵, A⁶ (see Figure 3) of the strikers that come into contact with the keys of the piano, 50 thereby raising the strikers into their inoperative position. The said plates when fully in completely cover the strikers and protect them and their operating devices from injury. These operating devices are 55 shown in Figure 3 as air pressure bellows A^{8x}, A^{8x} the movable elements of which form inclined planes upon which the edges of the plates operate to raise the strikers. When the piano player is in place on the piano for 60 use, the plates are withdrawn and the strikers are thus allowed to descend into contact with the keys a⁵, a⁶ of the piano.

In the case of a pneumatic or an electro-pneumatic piano player, cranks actuated by 65 the aforesaid hand plates or discs C, C¹

preferably operate bellows in the manner described in the specification of the aforesaid British patent.

The various parts of the improved piano player are intended to be made as light as is practicable so that the complete player can be made sufficiently light for easy carrying when folded as stated above and placed in the carrying case A^x. The possessor of a piano player of this description can therefore carry it about together with its accessories almost as readily as he would a violin.

The piano player when not arranged above the keyboard may conveniently be disposed in front of, and possibly at a somewhat lower level than, the keyboard and may be detachably connected to any convenient part of the piano, for example to the end blocks of the keyboard or to part of the wooden framework. In all instances however, the strikers operate upon the keys of the piano. The said piano player although preferably of a length at least equal to the normal length of the keyboard of an ordinary piano, may be shorter than the keyboard so that it only operates upon the keys of say four octaves instead of the normal seven octaves.

It is to be understood that the expression "piano player" herein employed is intended to include players for keyboard instruments similar to pianos.

What I claim and desire to secure by Letters Patent of the United States is:—

1. A piano player provided with strikers, comprising means for detachably connecting the player to a piano so that the strikers can operate upon the keys of the piano and means whereby the body of said player can be reduced in length after removal from the piano.

2. A piano player provided with strikers, comprising two main body parts, means for detachably connecting the player to a piano 110 so that the strikers of the player can operate upon the keys of the piano, and means for connecting said body parts together so that the player can be reduced in length after removal from the piano.

3. A piano player provided with strikers comprising two main parts, means for detachably connecting the player to a piano so that the strikers of the player can operate upon the keys of the piano, and means 120 for hinging said parts together so that one part can be folded against the other after the player has been removed from the piano.

4. A piano player provided with strikers comprising two main parts, means for detachably connecting the player to a piano so that the strikers of the player can operate upon the keys of the piano, and a vertical hinge for connecting said parts together so that they can be folded back to back after 130

the player has been removed from the piano.

5. A piano player provided with strikers, comprising two main parts, means for detachably connecting the player to a piano

6 so that the strikers of the player can operate upon the keys of the piano, means for connecting said parts together so that the player can be reduced in length after removal from the piano, air pipes carried by said parts,

10 plates movable with said parts into which plates the ends of said pipes are sealed, and means for establishing an airtight connection between the ends of said pipes as said plates are brought together by the movement of

15 said parts into the operative position.

6. A piano player provided with strikers, comprising two main parts, means for detachably connecting the player to a piano so that the strikers of the player can operate

20 upon the keys of the piano, means for hinging said parts together so that one part can be folded against the other after the player has been removed from the piano, air pipes carried by said parts, plates movable with

25 said parts into which plates the ends of said pipes are sealed, and means for establishing an airtight connection between the ends of said pipes as said plates are brought together by the movement of said parts into the op-

30 erative position.

7. A piano player provided with strikers,

having means for detachably connecting the player to a piano so that the strikers can operate upon the keys of the piano and a sliding member movable into position between the strikers and the keys.

8. A piano player provided with strikers, having means for detachably connecting the player to a piano so that the strikers can operate upon the keys of the piano and a 40 plurality of sliding members movable into position between the strikers and the keys.

9. A piano player provided with strikers, having means for detachably connecting the player to a piano so that the strikers can 45 operate upon the keys of the piano and a sliding member movable into position beneath the strikers and co-operating with inclined surfaces thereon during its movement into position.

10. A piano player provided with strikers, comprising two main parts, means for detachably connecting the player to a piano so that the strikers of the player can operate upon the keys of the piano, means for hinging said parts together so that one part can be folded against the other after the player has been removed from the piano and sliding members one carried by each of said parts and movable into position beneath the 55 strikers.

JOHN WEARHAM.
